RICHARD HAMMILL, OF MINERAL POINT, WISCONSIN.

Letters Patent No. 65,066, dated June 11, 1867.

IMPROVED EXTENSION-HORSE.

The Schedule referred to in these Letters Patent and making part of the same.

TO ALL WHOM IT MAY CONCERN:

Be it known that I, R. HAMMILL, of Mineral Point, Iowa county, Wisconsin, have invented a new and improved Extension-Horse; and I do hereby declare that the following is a full, clear, and exact description thereof, which will enable others skilled in the art to make and use the same, reference being had to the accompanying drawings, forming part of this specification, in which—

Figure 1 represents a side elevation of my improved extension-horse, when the same is contracted.

Figure 2 is a side elevation of the same, showing it extended.

Figure 3 is an end elevation of the same.

Figure 4 is a detail vertical cross-section on an enlarged scale, the plan of section being indicated by line *x x*, fig. 1.

Figure 5 is a detail horizontal sectional view, taken on the line *y y*, figs. 1 and 2.

Similar letters of reference indicate corresponding parts.

This invention relates to a horse or trestle which is used by masons, plasterers, and others, for supporting scaffolds, &c.; and it consists in so constructing the same that it can be raised or lowered, lengthened or shortened, and folded together, as may be desired, so that it will be adaptable for all purposes, and can, when made of one size, be extended to the very largest dimensions. A very convenient and practical instrument is thus made, and as it will combine in one all the sizes for which horses or trestles may be used, it will save a great expense to all who would otherwise need a number of different-sized articles. That it can be folded together for transportation and storing when not used is another great advantage of this invention.

A A represent the legs of the trestle, and B B are the main beam of the same. The beam B consists of two beams, which are connected by straps *a a*, of which one is firmly attached to the inner end of each beam and surrounds the other beam, thus connecting the two beams, but allowing them to slide so as to lengthen or shorten the beam as much as desired. Between the portions of the beam B is placed into grooves *g*, fig. 5, which are arranged in the inner sides of the said portions, a movable tongue or feather, *h*, on each end of which a pin, *i*, is arranged, which projects into that groove *g*, in which that end of the tongue slides. Across these grooves are arranged stops *k k*, against which the pins *i i* strike when the beam B is extended to its greatest extent, and which in combination with the bands *a* prevent the two portions of the beam from being separated altogether. To each end of the double beam B are secured two legs, A A, by means of pins *b b*. These pins are well shown in fig. 4. Each of them is provided with a head. The body is flat and slotted, the slot being closed at both ends, making the whole pin resemble a staple, the two ends of which are secured in the head. When the beam is extended, as in figs. 2 and 5, the tongue *h* strengthens the connections of the two parts of the beam, and keeps them in line, and prevents the centre of the beam from being depressed by a weight or from some other cause. The beam B is provided with holes cut through it, one for the reception of each pin *b*. A staple, *c*, is secured in each of these holes, and passes around one of the arms of the slotted pin *b*, through the slot in the same, as is clearly shown in fig. 4. Each pin passes through the upper ends of both legs A A, and through the end of the beam B, and a key, *d*, inserted between the end of the pin *b* and the side of one leg, A, through the slot in the pin, holds the parts together and the legs in position. By removing the key *d* the pin can be drawn back, as shown by red lines in fig. 4. By the staple *c* the pins are prevented from being altogether removed, as well as the legs A, but the legs can be folded to the beam, if desired, as soon as the keys are taken out. To each leg A are secured two metal bands, *e e*, which are large enough to surround an extension leg, D, of which one is provided to each leg A. The said extension leg is perforated with a number of holes, and a pin, *f*, passing through one of these holes and through the leg A, holds the extension leg in any desired position. To make the horse answer for great weights as well as for ordinary plasterers' use, different lengths of extension legs D may be provided for each one trestle. Thus the height of the apparatus can be easily regulated. To the under side of each band or strap *a* is hinged a brace, C, the lower end of which is hooked into a cross-brace, E, which is arranged between two legs A A, on either end of the trestle. The brace is applied to the inner end of one-half of the beam B, to which the legs are firmly secured by the pins *b*, with which legs the brace connects the end of the beam so that these braces do not interfere with the extension or contraction of the beam. One end of each of the cross-braces E is hinged to the upper band *e*, on one of a pair of legs,

A, and hooks into a ring or eye on the opposite band on the other leg of the same pair. When to be folded up the braces C are first unhooked and are folded to the beam. The braces E are then also unhooked and folded to the legs to which they are hinged. The pins f are then taken out of the legs A and D, and the extension legs are drawn in so as to be alongside the legs A; then the keys d are taken out and the legs folded to the beam, and the whole horse is completely folded up, but may be set up again in a very short time. The pins f and the keys d are attached to the beam and legs A, respectively, by small chains or strings, so that they cannot be lost.

I claim as new, and desire to secure by Letters Patent—

1. The manner of attaching the folding legs A A to the beam B of a horse or trestle, by means of slotted pins b, staples c, and keys d, all made and operating substantially as herein shown and described.
2. The extension beam B, in combination with the legs A D, all made and operating substantially as herein shown and described.
3. The braces C and E, in combination with the legs A and beam B, made so as to be folded to the beam and legs, if desired, as set forth.
4. Connecting and supporting the inner ends of the two halves of the extension beam B by means of bands a, and a tongue, h, which is provided with pins i i, and which is confined in grooves g between stops k, substantially as set forth.
5. An extension and folding horse or trestle, made and operating substantially as herein shown and described.

The above specification of my invention signed by me this 19th day of March, 1867.

RICHARD HAMMILL.
